PILOT STEM

Ernest A. Hall, Toledo, Ohio, assignor to The Hall Manufacturing Company, Toledo, Ohio, a corporation of Ohio

Substitute for application Serial No. 273,501, April 28, 1928. This application July 14, 1932, Serial No. 622,414

2 Claims. (Cl. 51—241)

This invention relates to a pilot stem, of improved construction, adapted to be used in connection with valve seat grinders and other tools which operate in a similar manner.

5 The present application is filed in substitution of an application Serial No. 273,501, filed April 28, 1928.

10 The object of the invention is to provide, for the purpose stated, a pilot stem or spindle which is so constructed that it may be easily and firmly secured in a valve stem guideway, and in connection therewith, to provide improved means for adjusting and centering the lower end portion of the stem within the guideway.

15 In using pilot stems, as heretofore commonly constructed, for the purpose of centering valve seat grinders and the like, it has been necessary to secure the pilot stem in proper position by applying a centering nut, expanding screw or equivalent means to the lower end of the stem after it has been inserted in the valve rod guideway. With the present invention, the entire pilot stem and adjusting means may be first assembled and then inserted through the upper end of the guideway, and after it has been thus inserted, the lower end may be easily adjusted and centered with respect to the guideway and the entire stem is held securely in correct position, even though the upper and lower ends of the 20 guideway are considerably worn.

25 The specific construction of the invention and the advantages resulting therefrom will be more particularly described in connection with the accompanying drawing, in which:—

30 Fig. 1 is a vertical section taken centrally through the lower part of the valve seat grinding tool and the adjacent portion of the motor, with the pilot stem secured in operative position.

35 Fig. 2 is an enlarged fragmentary section showing the expandable collet and expanding member in fully expanded position, the section being taken on line 2—2 of Fig. 3.

40 Fig. 3 is a detail plan view of the collet.

45 The internal combustion motor, a fragment of which is shown at 5, is formed with a cavity 6 which may represent a part of either the inlet or exhaust passage, and the wall of which is formed with a valve seat 7. Beneath the cavity 6 is a guideway 8 for the valve stem.

50 The valve seat grinding tool 10 may be of any suitable construction, preferably being provided with an eccentric bearing 12 adapted to be rotated about the pilot stem 13, which constitutes the subject matter of the invention. The main body 55 portion of the stem 13 has a diameter slightly less

than the diameter of the guideway 8 and is formed at its lower end with a reduced portion 14 which is threaded to receive an extension 15 which is formed at its upper end with a correspondingly threaded bore 16.

5 The body portion 13 of the stem is formed intermediate its ends with a downwardly facing conical enlargement 17, the base of which is somewhat larger than the internal diameter of the guideway 8. At the point where the main portion of 10 the stem 13 merges into the reduced portion 14, it is formed with a downwardly facing uniformly tapered portion 18 which is adapted to receive a collet 21. The dimensions of the stem are such that when the conical enlargement 17 is seated 15 in the upper end of the guideway 8 the tapered portion 18 is located within the guideway near the lower end thereof and the extension 15 projects below the end of the guideway.

20 The normal outside diameter of the collet 21 is slightly less than the diameter of the guideway 8 so that it may be easily inserted therein. The inner surface of the collet is tapered to correspond to the tapered surface 18. The collet has one side split, as shown at 22, so that as it is forced 25 upwardly on the tapered surface 18 it will be expanded and will be forced with increasing pressure against the wall of the guideway.

20 Longitudinal grooves 23 and 24 are provided on the internal surface of the collet to permit an 30 equal and easy expansion of this member.

When the pilot stem 13, the extension 15 and the collet 21 are assembled, the extension 15 is 35 screwed onto the reduced portion 14 sufficiently to retain the collet on the stem, but not far enough to expand the collet. When thus assembled, the stem may be inserted from the upper end of the guideway 8 and forced downwardly until the tapered enlargement 17 is firmly seated in the 40 upper end of the guideway. The extension 15 is then screwed up, forcing the collet upwardly over the surface 18, thus expanding the collet and causing it to bear forcibly against the wall of the guideway. At the same time the resistance of the collet against the wall of the guideway causes 45 the stem to be drawn more firmly against its seat.

50 In order to facilitate the insertion of the pilot stem and the adjustment of the collet to center the lower end thereof, transverse holes 25 and 26 are formed in the upper and lower ends respectively, for receiving cross rods.

55 The provision of the grooves 23 and 24 in the inner surface of the collet 21 facilitates the expansion of the collet. These grooves extend from

end to end of the collet and their bottoms are parallel to the periphery thereof.

In the expansion of the collet the outer surface will always maintain a substantially cylindrical shape. If the lower end of the guideway is enlarged by wear and is even elliptical in shape, the expanded collet will nevertheless effect a true centering of the pilot stem.

The depth of the bore 16 is so gaged that it will 10 act as a stop in screwing up the extension 15, before the expansion of the collet reaches its elastic limit, so that under no circumstances can the collet be accidentally broken by adjusting it too far.

15 After inserting the pilot stem in the guideway, it is not necessary to attach any nut, screw or the like to its lower end. All that it is necessary to do is to tighten the lower extension 15 by hand or by means of a cross rod inserted through the hole 20 26.

When the grinding of the valve seat has been completed, the extension 15 may be loosened sufficiently to permit the collet to work downwardly, or for the stem to work upwardly and permit 25 the collet to contract and disengage the wall of the guideway.

In the use of a pilot stem of the class described 30 it is highly important that the stem be truly centered with respect to the valve seat to be ground; otherwise an improper grinding is effected. Such

centering is difficult to obtain, especially when the stem is used in connection with a worn valve stem 35 guide, which condition is usually present to a greater or less extent where valve reseating is necessary. The wear occasioned in the guide usually effects a gradual enlarging of the guide from the centers outwardly in both directions and is also frequently elliptical or out-of-round in cross-section. It is, therefore, necessary to pro-

40 vide the pilot stem with guide engaging means which, when tightened, will cooperate with the guide to effect a true centering of the stem with respect to the valve seat. It is apparent that, if the lower end of the stem is so held that it is only one or two thousandths of an inch out of true 45 centering alinement with the guide opening, this will effect a considerably greater error in the centering of the upper end of the stem with respect to the valve seat. It is, therefore, important to have the engaging means of such a character

50 as to center the stem as nearly without any error in alinement as is possible. It is apparent that, if the stem does not aline accurately with the center of the valve seat, the grinding tool, which is guided by the stem, will effect a greater cutting of material from the valve seat at one side of its center than the other.

It is found in practice that with the use of an 60 expandible collet on the taper 18 of the stem, in conjunction with means for forcing the collet upward on the taper to effect the expanding action, a very accurate and effective centering of the pilot stem with respect to the guide is accomplished. It is also found that such centering is 65 rendered more accurate and positive irrespective

of an out-of-round condition of the guide, if the pilot is internally notched or weakened, as this seems to permit or effect a more uniform and true circular expansion of the collet than is the case if the weakening notches are provided on the external surface of the ring. For accurate and satisfactory centering of the stem in the guide it is found necessary and important to have as nearly a continuous annular expanding surface as is possible and at the same time permit the expanding action. Without this substantially continuous annular guide wall engaging surface of the expanding member, it is found practically impossible to obtain the same setting of a pilot stem twice in the same guide opening, particularly where the opening is slightly out-of-round, so that the stem when secured in the guide at one time would be off center in a different direction from that which it would assume when secured in the guide at another time. By 10 the use, however, of a split ring form of collet, as herein described, it is possible to secure the same setting of the stem with any guide opening each time it is mounted therein.

While I have shown and described specifically 15 one form in which the invention may be embodied, it is apparent that the details of the same may be modified in some respects without departing materially from the scope of the invention as claimed.

What I claim is:

1. The combination with a pilot stem adapted 20 to be inserted in a valve stem guideway, of means cooperating with the upper end of the guideway to center the upper part of the stem, a reduced tapered portion formed on said stem near its lower end, an expandible collet having a substantially continuous tapered internal face cooperating with the tapered portion of said stem, said collet having a plurality of weakened portions on its said internal face spaced inwardly of 25 its periphery whereby to equalize the expansion of said collet, and means connected to the stem to expand said collet by forcing the tapered portion of said collet into engagement with the tapered portion of the stem.

2. The combination with a pilot stem adapted 30 to be inserted in a valve stem guideway, of means cooperating with the upper end of the guideway to center the upper part of the stem, a reduced tapered portion formed on said stem near its lower end, an expandible collet having a substantially continuous tapered internal face cooperating 35 with the tapered portion of said stem, said collet having a plurality of axially extending grooves on its said internal face which extend through each of its ends and the bottoms of which are parallel to and spaced inwardly of the periphery of the collet whereby to equalize the expansion of the collet, and means connected to the stem to expand said collet by forcing the tapered portion of said collet into engagement with the tapered portion of the stem.

ERNEST A. HALL.
